MACHINE FOR SURFACE FINISHING

Byron F. Bower, St. Charles, Ill., assignor to The Howell Company, St. Charles, Ill., a corporation of Illinois

Application October 22, 1938, Serial No. 236,440

10 Claims. (Cl. 51—237)

The present invention relates to machines for finishing the surfaces of articles of different shapes and sizes. As an example, it is particularly applicable to polishing or buffing machines which are intended to treat the surfaces of articles which may be flat, annular or in the form of deep vessels.

In equipment of this character, the machines are generally used in the presence of some sort of abrasive. This makes the use of a sliding member to advance the work to the polishing wheel an unsatisfactory mechanism, because of the difficulty of maintenance. In the present device, any sliding ways which would be adversely affected by the abrasive are avoided.

In surface finishing of materials, the pressure per square inch of material pressing against the polishing wheel is an important factor in obtaining a proper surface. Generally speaking, it may be said that this pressure is a constant for each type of polishing operation. Therefore, if the pressure varies greatly during the polishing operation, the device is not functioning with maximum efficiency. It is well known that the wear of the finishing wheel makes it very difficult to maintain any given pressure of the material against the polishing wheel. Machines have been constructed in which partial correction of the variation in pressure due to wear on the wheel or other means is accomplished by the use of springs. The difficulty with this method, however, lies in the fact that springs are fixed values which prevent the ready correction and adjustments necessary for changes to different materials or parts to be polished. It is a fundamental purpose of this invention to provide a machine of the character described with means for applying the same pressure for urging the part against the wheel, the means being of such a nature that it can be adjusted quickly to a different pressure application for a different part or article to be polished.

It is a further object of this invention to provide a finishing machine of the character described with means whereby, as the finishing wheel wears, the article in contact with it is automatically advanced to compensate for the wear without any attention from the operator, the pressure in the advanced position being the same as in the previous position.

It is also a purpose of the present invention to provide a machine of this character wherein the control for moving the work to the wheel is such as to avoid any mechanical toggle arrangements which require considerable strength on

the part of the operator to bring the work into operative position. In this respect, the machine, as shown hereinafter, includes an advancing control means whereby the operator may, by a single movement such as the operating of a foot pedal, move the work from loading position into finishing position, and then apply the necessary pressure of the work against the finishing wheel, without further attention being necessary. The machine, of course, may be made more or less automatic by the use of known electrical timing equipment for actuating the control means.

In particular, it is a purpose of the present invention to provide in a surface finishing machine a mechanism having means for grasping the work placed upon a holding chuck, then advancing the work to a finishing wheel and thereafter applying the work to the finishing wheel with a pressure which does not vary due to the wear of the wheel, and turning the work as may be necessary to treat all parts of it. Also, the invention contemplates means applicable to multiple chucks for moving a finished piece of work to a point where it may be removed while another piece of work is being polished without in any way varying the pressure of the work against the wheel.

Further and more detailed objects and advantages of the invention will appear more fully as the description proceeds, reference being had to the accompanying drawings wherein a preferred form of the invention is shown. It is to be understood, however, that the drawings and description are illustrative only, and are not to be taken as limiting the invention except insofar as it is limited by the claims.

In the drawings, Fig. 1 is a view in side elevation, with certain parts in section, of a finishing machine embodying my invention;

Fig. 2 is an end view of a more complete form of the invention which is particularly adapted for moving hollow parts over a finishing wheel and thereafter applying them to the wheel so as to finish the interior surface thereof;

Fig. 3 is a view in side elevation of the machine shown in Fig. 2;

Fig. 4 is a diagrammatic view illustrating the pneumatic circuit by which the several operations are controlled from a simple foot operated valve;

Fig. 5 is a view in side elevation of a chuck head showing a multiple chuck by which a plurality of pieces may be held against a finishing wheel;

Fig. 6 is an enlarged view in side elevation of the chuck head with a multiple chuck attached thereto; and

Fig. 7 is an end view looking at the left-hand end of Fig. 6 with a part of the end plate of the chuck broken away to show the interior construction.

Referring now in detail to the drawings, and particularly to Fig. 1, the present invention is shown there as embodied in a machine wherein the work is held by a chuck 10 which is mounted upon a chuck head 11 that, in turn, is supported by a stem 12. The stem 12 is pivoted upon a base 13 so that the chuck head may be swung with the stem toward and away from a finishing wheel 14.

The finishing wheels for final polishing operations are driven at a very high speed. They are usually constructed of a fabric and are treated with an abrasive material which they apply to the article to be polished as it is held against the wheel. The quality of finish imparted to the surface of the article and the efficiency with which the wheel does its work both depend upon the pressure of the wheel against the material. Most finishing wheels wear very rapidly and their diameters are therefore continuously changing.

The present invention provides means whereby the chuck head is made to follow the wheel and force the work against it with the same unvarying pressure as the wheel is worn away. In order to accomplish this result, the stem 12 is provided with an arm 15, by which the stem may be rocked on its pivot, to move the work into and out of engagement with the wheel. The arm 15 is moved by a cylinder 16 and a piston rod 17 which are interposed between the arm 15 and the base 13. A piston 18 on the rod 17 slides within the cylinder 16 under air pressure which is supplied from a suitable source through the connections 19 and 20. By controlling the source of air pressure and the rate of flow of air to the cylinder 16, the operator may control the speed at which the chuck 10 is advanced to the wheel 14 and the polishing pressure which is maintained between the wheel 14 and a part such as the ring 21 that is being polished.

For convenience in adapting the machine to different sizes and shapes of work, the stem 12 is made up of a plurality of parts linked together to provide for angular and longitudinal adjustments. These parts comprise a bottom section 22 which is pivoted upon a shaft 23 carried by up-standing ears 24 on the base 13. The bottom section 22 has a sleeve 25 mounted thereon, the sleeve being vertically adjustable as well as rotatable upon the section 22. Vertical adjustment is obtained by a screw threaded partition 26 in the section 22 and a screw bolt 27 carried by a head 28 of the member 25. The bolt 27 is rotatably mounted in the head 28, being held against vertical movement with respect to the head by the bolt head 29 and a nut 30 that is fastened to the bolt 27 by a pin 31. The member 25 is slotted vertically and provided with clamping ears shown at 32 which may be fastened together by a bolt 33. By releasing the bolt 33 the member 25 can be turned on the section 22 to provide for angular adjustment. Then when the bolt is tightened the adjustment will be maintained.

The member 25 has a laterally extending arm 34 to which an upwardly projecting tubular stem 35 is fastened by means of a pin 36. On the stem 35 a sleeve 37 is rotatably mounted. This sleeve, like the member 25, is split through the greater

part of its length and can be clamped in place by means of a bolt 38 that extends through ears 39 provided on the sleeve 37. The sleeve 37 has a horizontally extending arm 40 which carries at its outer end another sleeve 41. The sleeve 41 has fixed therein an upwardly extending sleeve 42 on which a chuck head mounting bracket 43 is clamped. The bracket 43 is split in the same manner as the sleeve 37, so that it can be clamped to the upper end of the sleeve 42. The chuck head 11 has a depending bracket 44 which overlaps the bracket 43 and is secured thereto by a bolt 45 which acts as a pivot upon which the chuck head may be adjusted. The bracket 44 has an elongated slot 46 through which a bolt 47 extends to clamp the head 11 in position.

The chuck head 11 comprises a tubular casting 48 having an enlarged gear housing portion 49 at one end. On the casting 48 there is mounted a motor support 50 comprising a lower plate 51 fastened directly to the casting and an upper plate 52 which carries a motor 53. The upper plate is pivoted to the lower plate by a shaft 54 and is adjustable about the shaft 54 by means of an eye bolt 55 which is pivoted on the lower plate 51 and the adjusting nuts 56 and 57 on opposite sides of the plate 52. The casting 48 has ball bearings 58 and 59 supporting a hollow shaft 60. The shaft 60 is held against endwise movement in one direction in the casting 48 by an end plate 61, the bearing 58 and a collar 62. The bearing 59 and a nut 63 screw threaded on the shaft 60 prevent endwise movement of the shaft 60 in the other direction.

The chuck 10 is mounted upon a projecting portion 64 of the shaft 60 and may be fixed thereto in any suitable manner, as will be readily understood. At the other end of the shaft 60 a worm gear 65 is keyed to the shaft and meshes with a worm 66 that is journalled in the housing 49. The worm 66 projects from the housing and is provided with a pulley 67 which is connected to a pulley 68 on the motor 53 by means of a belt 69. An end plate 70 covers the outer end of the housing 49.

Means are provided for actuating the chuck 10 from a source of fluid pressure which also moves the chuck into operative position with respect to the finishing wheel. The chuck 10 has radially movable portions 71, only one of which is shown in elevation in Fig. 2. These radially movable portions are adapted to move out into engagement with the work 21. To move the portions 71, bell crank levers 72 are provided, these levers being pivoted upon pins 73 in the rim of the chuck 10. The inner ends 74 of the levers 72 fit in a groove 75 of an axially movable chuck setting member 76. The member 76 has a stem 77 on which it is screw threaded, and this stem extends into the portion 64 of the shaft 60. The stem 77 has a reduced portion 78 and a set screw 79 extends into the passage through the shaft 60 to limit the movement of the stem 77.

The member 76 is shown in released position in order to advance it to cause the chuck to grasp a work piece 21. I provide a piston rod 80 which extends through the shaft 60 and is adapted to engage the stem 77. A suitable ball bearing 81 is provided between the stem 77 and the rod 80. The rod 80 extends into a cylinder 82 which is mounted on the end plate 70. A piston 83 is mounted on the end of the rod 80 within the cylinder 82. The cylinder 82 comprises an end plate 84 fitting against the end plate 70 and provided with a stuffing box 85 for the piston rod 80, a

second end plate 86 and a tubular cylinder 87. The end plates 84 and 86 are provided with air inlets 88 and 89, so that air under pressure may be admitted to either side of the piston 83. Bolts 90 mount the entire cylinder assembly 82 upon the end plate 70.

In certain types of work, particularly in the polishing of the interior of hollow vessels, it is desirable to have a device of this character 10 wherein the work, after being mounted on the chuck, can be advanced axially of the finishing wheel until the wheel is brought inside the hollow article. In this position it is then necessary to move the work against the wheel with the 15 necessary pressure. In Figs. 2 and 3 of the drawings there is illustrated a modification of the present device particularly adapted for this purpose. It will be understood that the chuck arm 44 illustrated in Figs. 2 and 3 carries the chuck 20 mechanism shown in Fig. 1 and a suitable chuck for gripping hollow articles. The structure of the member 43 and its connection to the chuck arm 44 remains the same in the modification as in the main form of the device which is described.

25 The member 43 is supported upon a stem 91 which is fixed upon a shaft 92. The shaft 92 is journaled in two spaced standards 93 and 94 which are mounted upon a horizontally moving table 95. The stem 91 has an arm 96 fixed thereto. The table 95 has a bracket 97 extending in the same plane as the arm 96, the bracket 97 being turned down and then outwardly to provide a support for an air cylinder 98. The air cylinder 98 is shown as pivoted by a pin 99 to the end of 30 the arm 96 and as having a piston 100 therein, the piston rod 101 of which is pivoted by a pin 102 to the bracket 97. It is evident that by applying air against the piston 100 the arm 96 can be moved up or down to force a chuck carried by 40 the member 43 to move its work into and out of engagement with a finishing wheel.

In order to move the chuck head to the finishing wheel so that a hollow article held by the chuck will go over the wheel, means are provided whereby the table 95 is shifted axially of the finishing wheel and at right angles to the plane of movement of the arm 96. A base 103 carries a vertically adjustable stem 104. The stem 104 may desirably comprise a screw threaded tubular sleeve which threads into an adjusting wheel 105 that rests on top of the base 103. The base 103 is split, as shown at 106, and is provided with ears 107 and 108 that can be drawn together by a bolt 109 to clamp the stem 104 in 55 place.

The stem 104 supports a casting 110. The casting 110 has a depending boss 111 which is mounted on pins 112 and 113 projecting from the stem 104. The casting 110 has guides 114 and 60 115 upon which a supporting block 116 is slidably mounted. An adjusting shaft 117 is journaled in the casting 110 and threaded through a depending lug 118 on the block 116.

The block 116 has means thereon for supporting the table 95 for endwise movement. This means comprises a frame 120 which is bolted to the block 116 by two L-shaped standards 119. The frame 120 carries four rollers 121. These four rollers in turn carry the table 95. The table 95 has bearing surfaces 122 and 123 over the rollers 121. Upon one side of the table 95 a bar 124 is fastened to provide a bearing surface underneath the rollers 121. A similar bar 125 forms a lower bearing at the other side of the table 75 for the rollers 121. It is understood, of course,

that there is sufficient clearance between the upper and lower bearings to prevent any roller from engaging both bearings at the same time. The table 95 also has a guide slot 126 running lengthwise thereof and a guide bar 127 is bolted to the 5 frame 120.

An air cylinder 128 is also bolted to the frame 120. Air connections are provided at 129 and 130 for supplying air to either end of the cylinder 128. A piston 131 in the cylinder 128 has a 10 piston rod 132 which is connected to a bracket 133 at one end of the table 95. By supplying air to the cylinder 128 the operator may shift the table 95 to and from the finishing wheel.

The valve arrangement by which fluid under 15 pressure is supplied to the several cylinders is shown diagrammatically in Fig. 4. For the sake of convenience in explanation of the present system, I have shown in Fig. 4 the complete air supply circuit for the double acting machine shown 20 in Figs. 2 and 3. It will be understood, of course, that where the horizontal table 95 is not being used, the connections for the cylinder 128 would not be necessary.

25 Referring now to Fig. 4, air is supplied from a suitable source through a hose 134. A throttling valve 135 is provided in the hose 134, and a reducing valve 136 is also provided in the hose 134. The air is supplied to a control valve 137 which, as shown herein, is a four-way foot pedal operated valve. The showing of the valve 137 is diagrammatic, as will be readily understood. The particular structure of the valve may, of course, be varied and no claim is made to any structural features of the valve used.

35 The valve 137 has one port 138 connected to the supply hose 134. It has another port 139 connected by hose 140 direct to the advancing side of the piston 83 in the chucking cylinder 82. The port 139 is also connected by a hose 140a to 40 the advancing side of the piston 131 in the table advancing cylinder 128. This connection, however, is through a spring loaded relief valve 141 that will not open until the piston 83 is moved and pressure builds up in the hose 140. As shown, 45 the valve is arranged so that when a foot lever 142 is depressed, air connections are established between the ports 138 and 139.

Exhaust ports are provided at 143 and 144 for 50 exhausting air from the valve 137. These exhaust ports are connected together to a discharge hose 145. A fifth port 146 leads from the valve 137 direct through a hose 147 to the pull back side of the cylinder 100.

In order to supply air pressure to the advancing side of the cylinder 100, or in the event the table is not being used to the cylinder 100, a connection is provided from the hose 140a through a spring loaded relief valve 148 to a hose 149 that leads to the advancing side of the cylinder 100. 60 The valves 141 and 148 are valves which do not open until the pressure built up in the supply line exceeds a certain value. In order to lead off the air in the hose 149 and in the cylinder 100, by-passes 150 and 150a are provided around the 65 relief valves 141 and 148. These by-passes are controlled by check valves 151 and 151a.

Air is supplied to the pull back end of the cylinder 128 from the hose 147 through a spring loaded relief valve 152. This valve is by-passed 70 also by a connection 153 having a check valve 154 therein. Between the relief valve 152 and the cylinder 128 a hose 155 is led off through a relief valve 156 to the release side of the piston 83 of the chuck actuating cylinder 82. The relief 75

valves 152 and 156 are arranged so that valve 152 opens and causes the return of the piston 131 before enough pressure is built up to open the relief valve 156. This enables the chuck to hold 5 its work until the table has returned to its original resting position. The relief valve 156 is also by-passed by a connection 157 with a check valve 158 therein.

In order that the operation of the system will 10 be fully understood, a brief description of one complete cycle of operations will be given. It will be assumed that the operator has just pressed down upon the foot lever 142 to move the valve heads 159 and 160 in the valve 137 to the position 15 shown in Fig. 4. Air is passed through the valve 137 from port 138 to port 139 and flows out 20 through the hose 140. This supplies air first to the chucking cylinder 82 and then to the table cylinder 128. The chucking cylinder being small and having a light load, it will immediately actuate the chuck to grasp the article. The table 95 will start to move toward the finishing wheel as soon as enough pressure builds up in the hose 140 to open the relief valve 141, and will continue to move until the article to be polished is 25 brought over the wheel. When the piston 131 reaches the limit of its stroke, pressure will build up in the hose 140a and open the relief valve 148. When the relief valve 148 opens, it supplies 30 air to the advancing side of the cylinder 100. The pressure builds up to the desired value. This value is controlled by the reducing valve 136. The work is held against the finishing wheel until the polishing operation is completed. It will be 35 noted that during this time the hose 147 is connected through the ports 146 and 143 to the exhaust line 145.

When the polishing operation is completed, the operator takes his foot off the lever 142 and a 40 spring 161 moves the valve heads 159 and 160 to the left to connect ports 138 and 146 and connect port 139 with exhaust port 144. The pressure on the advancing side of the piston in the cylinder 100 is immediately released through the 45 hose 149, by-passes 150 and 150a and check valves 151 and 151a. Similarly, the pressure on the advancing sides of the pistons 83 and 131 is released. Air pressure is supplied through the hose 147 to the pull back side of the piston in the cylinder 100. This causes the work to be moved 50 away from the finishing wheel before the table 95 is moved back, and before the chuck operating cylinder is caused to release the chuck. When the piston in the cylinder 100 has completed its 55 travel, pressure builds up to open the relief valve 152 and admit air to the pull back end of the cylinder 128. The piston 131 is moved to the right, as shown in Fig. 4, to the end of its stroke, thus withdrawing the work from over the finishing wheel. The pressure then builds up in the 60 hose 155 and opens the relief valve 156 to supply air to the pull back side of the piston 83 in the chucking cylinder 82, and return the piston to chuck releasing position. This returns the parts 65 to their original position, ready for another cycle.

In Figs. 5, 6 and 7 I have shown a slightly different form of chuck arrangement on the chuck head 11. This is a hand chucking device by 70 which a plurality of parts such as are indicated at 162 may be polished. As an example of the utility of this chucking device, I have shown the chuck as holding a plurality of sole plates for pressing irons. The chuck consists of the end plates 163 and 164. The end plate 164 is coupled 75 directly to the stem 60 of the chuck head 11.

A plurality of article holding plates 165 are fastened to the end plates 163 and 164 by screws, such as are shown at 166. These plates 165 have seats for the articles 162 and in the present instance each plate has an aperture 167 through which a portion of the article 162 extends. With the sole plates of the irons, this portion is shown as the screw threaded bosses which are provided for mounting the sole plates. A clamping bar 168 is provided for each article. This clamping bar 10 is pivoted in the end plates 163 and 164 so as to swing against the projecting portion of the article and clamp it against a side edge of the opening 167. To effect the clamping action a cam shaft 169 is mounted back of the bar 168, the shaft 15 having its bearings in the end plates 163 and 164. Clamping handles 170 are provided for the cam shafts 169.

Owing to the nature of the control by which the chuck head is moved to bring the work against 20 the finishing wheel, the entire chuck head can move toward and away from the wheel as the chuck is rotated by the motor 53. Articles of irregular contour can thus be finished with the same pressure control as articles of regular, 25 angular contour.

Articles of irregular contour can be mounted on the chuck head by means of a suitable chuck. They will follow the wheel at all times. This is because the chuck is yieldingly pressed against 30 the wheel by the air pressure in the pressure cylinder 16. If the wheel is riding on a high part of the article, the chuck is pushed back against the air pressure in the cylinder 16, but when the high part of the article moves past the wheel the 35 air pressure advances the chuck to maintain the pressure of the article against the wheel.

It is not necessary to remove the chuck from the wheel to change articles. This will be evident from a study of Figs. 5, 6 and 7. It is 40 obvious that while one sole plate on the chuck is being held against the wheel the opposite sole plate can be removed and replaced without stopping the chuck. The speed of rotation of the chuck is, of course, very slow. For example, in 45 the form shown, it is about 1 R. P. M. The polishing of articles on a multiple chuck therefore can be continuous insofar as the operation of the finishing wheel and maintenance of an article against it are concerned.

From the foregoing description it is believed that the features and advantages of the present invention will be readily apparent to those skilled in this art. Having thus described my invention, what I claim as new and desire to secure by 55 Letters Patent is:

1. In a surface finishing machine, a work holding chuck, a finishing wheel, a swinging supporting head for said chuck, a stem carrying said head, and a base, said stem being pivoted on the 60 base, and control means adapted to move the chuck head to bring the work against the finishing wheel and hold it against the wheel, said control means comprising a cylinder, a piston therein having a piston rod projecting from the cylinder, 65 an arm on the stem, said cylinder and piston rod being interposed between the arm and said base, and means to direct fluid under pressure to either side of the piston in said cylinder.

2. In a surface finishing machine for imparting 70 a finish to the surface of articles by pressing them against a rapidly moving finishing member, a pivoted chuck head having a mechanism thereon to turn the articles to bring different parts into engagement with said member, and 75

fluid pressure operated means operatively connected to said chuck head to swing the articles to and from the member and press the articles carried thereby against said member.

5. 3. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 10 means comprising an arm for moving said head and a cylinder and piston for actuating the arm.

4. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 15 means comprising a support carrying said head, a bracket on said support, an arm connected to said head for moving it, and a fluid cylinder and piston interposed between the arm and bracket.

5. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 20 means comprising a support carrying said head, a frame movably mounting the support, a fluid piston and cylinder on said frame for moving the support, a bracket on said support, an arm connected to said head for moving it, and a fluid cylinder and piston interposed between the arm and bracket.

6. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 25 means comprising a support carrying said head, a frame movably mounting the support, a fluid piston and cylinder on said frame for moving the support, a bracket on said support, an arm connected to said head for moving it, and a fluid cylinder and piston interposed between the arm and bracket, and a control valve system connected with said cylinders for operating them in a predetermined sequence.

7. In a surface finishing machine for imparting a finish to the surface of articles by pressing

them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said chuck head including a chuck having separate seats thereon to hold a plurality of articles in circumferentially spaced 10 relation thereon and means individual to each seat for holding the articles whereby one article may be replaced while another is being finished.

8. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 15 means comprising an arm for moving said head and a cylinder and piston for actuating the arm, said chuck head including an article clamping chuck and a fluid pressure cylinder and piston actuating said chuck.

9. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 20 means comprising an arm for moving said head and a cylinder and piston for actuating the arm, said chuck head including an article clamping chuck and a fluid pressure cylinder and piston actuating said chuck, and a control valve system connected with said cylinders for operating them in a predetermined sequence.

10. In a surface finishing machine for imparting a finish to the surface of articles by pressing them against a rapidly moving finishing member, a pivoted chuck head having a mechanism thereon to turn the articles to bring different parts into engagement with said member, and fluid pressure operated means operatively connected to said chuck head to swing the articles to and from the member and press the articles carried thereby against said member, said fluid pressure operated 25 means comprising a support carrying said head, a frame movably mounting the support, a fluid piston and cylinder on said frame for moving the support, a bracket on said support, an arm connected to said head for moving it, and a fluid cylinder and piston interposed between the arm and bracket, said chuck head including an article clamping chuck and a fluid pressure cylinder and piston actuating said chuck, and a control valve system connected with said cylinders for operating them in a predetermined sequence.
